UNITED STATES PATENT OFFICE

2,514,599

ILLUMINATED ADVERTISING DEVICE

Charles L. Dwinell, Kansas City, Mo.

Application February 9, 1948, Serial No. 7,125

2 Claims. (Cl. 240—10)

1

This invention relates broadly to the field of advertising and particularly to a device for more clearly displaying advertising material, the primary object being to provide a device capable of more effectively setting forth an advertising figure or the like than has heretofore been possible.

The most important object of this invention is the provision of an advertising device of an upright figure mounted within a hollow open face body and provided with illuminating means so disposed as to effectively light the figure.

Another important object of this invention is the provision of an advertising device as above set forth wherein the illuminating means is provided with a guard plate formed to permit passage of light rays from the illuminating means within an area defined only by the periphery of the figure.

Other objects of this invention lie in the way light is directed to an area surrounding the periphery of the figure; the way in which the front face of the figure is lighted by a second illuminating device; and the manner in which the aforesaid guard plate serves to separate the two illuminating mediums.

Other objects will be made clear or become apparent during the course of the following specification, reference being had to the accompanying drawing, wherein:

Fig. 1 is a front elevational view of an advertising device made in accordance with my present invention.

Fig. 2 is a substantially central cross-sectional view taken on irregular line II—II of Fig. 1; and

Fig. 3 is a fragmentary cross-sectional view taken on line III—III of Fig. 1 looking in the direction of the arrows.

In the field of advertising many times it is desirable and advantageous to set forth a product to be sold in the form of an indicating figure or the like therefor. Such figure will more effectively attract the eye of the prospective purchaser if the individual colors thereof are illuminated and the figure made to appear as animated as possible. To this end, a figure, broadly designated by the numeral 10, has been illustrated and takes the form of a parrot or like bird. Consequently the many colors of such figure 10 should be brought out as clearly as possible.

This figure 10 is preferably made from a light weight material that is easily cut and molded, and in the instance illustrated, plastic has been found to be most suitable. The various colors of the bird forming the figure 10 are painted or otherwise placed upon one face of the plastic ma-

2

terial forming the figure 10, to render the same for the most part, translucent. In some cases as at 12 and 14, and also along the entire marginal edge of the figure 10, the plastic material is left entirely transparent.

This figure 10 is mounted on a transverse plastic bar 16 by fusing or otherwise affixing the claws 18 of bird 10 directly thereto. This bar or rod 16 extends transversely across an open face of a hollow body, broadly designated by the numeral 20. This body 20 is generally cup-shaped and also made from a translucent plastic material or the like.

It is preferable that this entire body 20 with the exception of a continuous rim 22 defining the open face thereof and suitably fused to the main body 20, be of a solid color and the band 22 being of a contrasting color. The lowermost portion of the hollow body 20 is formed to present a hollow base portion 24 upon which the entire device rests.

A guard plate 26 is disposed directly behind the figure 10 and is provided with a laterally turned flange 28 resting upon a bottom wall 30 of the base 24 affixed thereto through the medium of bolts or the like 32. This guard plate 26 extends from the bottom wall 30 of the base portion of body 20 upwardly and terminates in spaced relation from the uppermost end of the figure 10. The uppermost portion of the guard plate 26 is circular as clearly illustrated in Fig. 1, merging with a rectangular portion forming the lowermost part of guard plate 26.

The figure 10 and guard plate 26 are interconnected by a plurality of bolts or the like 34 having spacers 36 interposed between guard plate 26 and the figure 10 to hold the same in spaced apart relationship. The head of the lowermost bolt 34 is disposed within the base portion 24 of body 20 to be entirely hidden from view and the heads of the other bolts 34 are disposed in alignment with the cross member 16 which is semi-circular in cross section, as clearly illustrated in Fig. 2.

A substantially Y-shaped notch 38 is cut in the guard plate 26 directly in alignment and behind the figure 10 and a reinforcing bar 40, disposed in transverse relationship to this notch 38, serves to maintain guard plate 26 in a substantially flat rigid condition.

50 A pair of L-shaped brackets 42 and 44 each having one leg thereof affixed to the normally rearmost face of the guard plate 26 by bolts or the like 46, support a pair of lamps 48 and 50 respectively. These lamps 48 and 50, as well as a lamp 52 mounted within the base 24, are con-

nected to a suitable source of electrical energy (not shown) by means of lead wires 54.

The lamp 48 is elongated and disposed in alignment with the lowermost and narrowest portion of the notch 38, whereas the lamp 50 is arranged above lamp 48 and in alignment with the wider portion of notch 38 formed in the guard plate 26. Lamp 52 is mounted upon a bracket 56 secured directly to the bottom plate 30 of hollow base 24 immediately below and in front of figure 10.

A front panel 58 forming a part of the base 24 and extending forwardly of the rim 22 defining the opening within body 20, is also formed from initially transparent material having a coating 60 of paint or the like to render the same translucent and having areas covered with a relatively light colored paint to define advertising indicia 62.

In operation, when the lamps 48, 50 and 52 are illuminated, rays of light emanating from lamps 48 and 50, will pass through the notch 38 formed in the guard plate 26 and pass through the translucent and transparent portions of figure 10 to illuminate the same and set forth clearly, all of the individual colors of such figure 10.

The guard plate 26 has its notch 38 formed as to confine the rays of light emanating from lamps 48 and 50 to an area within the marginal edges of figure 10 and this effect is enhanced by the provision of laterally turned flanges 64 extending toward the figure 10 throughout the entire periphery of notch 38. Inasmuch as the body 20 is bowl-shaped, other rays of light coming from lamps 48 and 50 will be diffused laterally from such lamps 48 and 50 and outwardly around the entire area circumscribing the figure 10. Certain of such diffused rays of light will strike the band 22 and be deflected inwardly toward the normally front face of bird 10. By the same token, the lamp 52 will direct its rays of light upwardly and inwardly toward the normally front face of figure 10 and cooperate with the lamps 48 and 50 in positively illuminating and setting forth all of the colors of the figure 10.

It is preferable that the coating 60 for the base 24 be of a color contrasting with the color of rim 22 and main portion of body 20 and also that the front face of guard plate 26, be painted in suitable contrasting colors.

When the device formed as above described is placed in operation and disposed in a suitable position where the same can be easily seen by the

public, a very attractive advertising device is presented and the desired attractive and extremely noticeable figure 10, will undoubtedly divert the attention of such observers.

It is to be understood that the figure 10 herein shown is for illustrative purposes only and that the broad concepts herein set forth may well be used for various and numerous advertising mediums. Details of construction may also be varied without departing from the spirit of this invention or scope of the appended claims.

Having thus described the invention, what is claimed as new and desired to be secured by Letters Patent is:

1. An advertising device of the character described comprising a figure of translucent material; a hollow body of opaque material partially surrounding said figure; illuminating means for said figure disposed between a portion of the body and one face of said figure; means for confining certain rays of light from said illuminating means within the marginal edges of said figure; and means for redirecting additional rays of light emanating from said illuminating means against the opposite face of the figure.

2. An advertising device of the character described comprising a figure of translucent material; a hollow body of opaque material partially surrounding said figure; illuminating means for said figure disposed between a portion of the body and said figure; means for confining certain rays of light from said illuminating means within the marginal edges of said figure; and a second illuminating means disposed to direct rays of light toward said figure in a substantially opposite direction to said first mentioned rays of light, said confining means being formed to separate the rays of light emanating from said first mentioned and from said second illuminating means.

CHARLES L. DWINELL.
